DESIGN FOR A DIAMOND DRESSING TOOLHOLDER

Jerry Krandall, Detroit, Mich., assignor to Abrasive Dressing Tool Company, Detroit, Mich., a partnership of Michigan

Application May 11, 1944, Serial No. 113,553

Term of patent 7 years

(Cl. D37—1)

To all whom it may concern:

Be it known that I, Jerry Krandall, a citizen of the United States, residing at Detroit, in the county of Wayne and State of Michigan, have invented a new, original, and ornamental Design for a Diamond Dressing Toolholder, of which the following is a specification, reference being had to the accompanying drawing, forming part thereof.

Fig. 1 is a top plan view of a diamond dressing toolholder showing my new design.

Fig. 2 is a side elevation of the same.

Fig. 3 is a bottom plan view of the same.

I claim:

The ornamental design for a diamond dressing toolholder, substantially as shown.

JERRY KRANDALL.
